Edward J. Carlin, Brooklyn, N. Y.

Application August 26, 1955, Serial No. 530,844

10 Claims. (Cl. 36—36)

This invention relates to heels for shoes, boots and other footwear, and more particularly to new and useful improvements in rubber heels for men's shoes.

A principal object of the present invention is to provide a rubber heel which is readily applied to the heel of a shoe and which is securely held in position thereon.

Other objects and advantages of the invention will be apparent from the description thereof to follow taken in connection with the accompanying drawings in which—

Fig. 1 is a fragmentary side elevational view of a shoe with a heel embodying one form of my invention applied thereto.

Fig. 2 is a top plan view of the heel removed from the shoe.

Fig. 3 is a vertical sectional view taken on the plane of the line 3—3 of Fig. 1.

Fig. 4 is a similar view but showing the clamps in open inoperative position.

Fig. 5 is a fragmentary sectional view showing the clamp only partly closed.

Fig. 6 is a top plan view of the skeleton frame removed from the heel.

Fig. 7 is a front view thereof.

Fig. 8 is an enlarged detail view taken on the plane of the line 8—8 of Fig. 6, looking in the direction of the arrows.

Fig. 9 is an enlarged horizontal sectional view taken on the plane of the line 9—9 of Fig. 7.

Fig. 10 is a view similar to Fig. 6 but showing a modified form of frame.

Fig. 11 is a front view of a modified form of clamping device.

Fig. 12 is a vertical sectional view taken on the plane of the line 12—12 of Fig. 11.

Fig. 13 is a view similar to Fig. 11 but showing another modified form of clamp.

Fig. 14 is a vertical sectional view taken on the plane of the line 14—14 of Fig. 13.

Fig. 15 is a detail view taken on the plane of the line 15—15 of Fig. 13 and looking in the direction of the arrows.

Referring now to the drawings in detail and particularly to Figs. 1 to 9, inclusive, showing the first form of the invention, in Fig. 1 there is shown a fragment of a man's shoe 20 comprising an upper 21 and an outer sole 22 having a heel portion 23. A heel 24 made in accordance with the present invention is mounted on the heel portion 23 of the shoe.

The heel 24 comprises a thick body 25 of rubber. Embedded in the body 25 of the rubber heel there is a frame 26 (see Fig. 6) formed of flat stainless steel and consisting of an outer frame member 27 of substantially horse-shoe shape and an inner frame member 28 of similar shape. The frame members are joined together midway their ends and held in spaced relation by a double headed rivet 29, the free ends of the frame members being each formed with aligned slots. A flat strip or plate 30 extends across the space between said free

2

ends and through said aligned slots and disposed perpendicularly to the frame members and is secured in any suitable manner. The plate 30 extends laterally beyond the ends of the outer frame member 27 as shown in Fig. 6. Another plate 31 similar in length to plate 30 but of lesser width is spaced forwardly of plate 30 and is rigidly connected thereto by a pair of spaced plates 32, 32, plate 31 extending through aligned slots in the inner end of the plates 32, 32 and plate 31 extending through similar aligned slots in the outer end of said plates 32, 32. The plates 32, 32 are fastened to the plates 30 and 31 in any suitable manner.

Frame 26 is embedded in the material of the body 25 preferably by placing the frame in a mold and pouring the molten rubber forming the body of the heel over the frame so that the molten rubber will be bonded to the frame, with a narrow layer of rubber of approximately $\frac{1}{16}$ " above the upper edge of the frame members 27 and 28, and with a thick layer of approximately $\frac{5}{16}$ " below the lower edges thereof as shown in Fig. 3. The plates 30 and 31 are sufficiently long to extend beyond both sides of the body 25 of the heel and pivotally mounted on the extending ends thereof in slots 35 in the ends of plate 30 and in similar slots in the ends of plate 31 there are clamping devices 37 and 38.

The clamping devices are similarly constructed and each comprises a substantially triangular-shaped body 40 of stainless steel. The body portion 40 is slightly curved transversely to conform to the curvature of the body 25 of the heel 24 and is formed with a flat inwardly extending flange 41 which slants slightly downwardly. Depending from the apex portion of the body 40 is an integral narrow strap portion 42 turned upon itself midway its ends and extending upwardly therealong forming a looped bearing portion 43 and a curved finger portion 44 overlapping the strap portion 42. A pivot pin 45 extends through the looped bearing portion 43 with its ends projecting outwardly thereof at both ends. The strap portion with its curved finger portion 44 extends loosely through its respective slot 35 in the plate 30 or plate 31, with the pivot pin 45 disposed therebelow.

A locking latch indicated generally at 46 is pivotally supported by the pin 45. The latch comprises a finger 47 having perforated ears or wings 48 at its inner end through which loosely passes the pin 45. The inner end of each ear 48 is cut at an acute angle to the plane of the finger 47 producing a pointed inner end 49 on each ear. The free end of the finger 47 is curved inwardly.

The heel 24 is applied to the heel portion 23 of the shoe and initially fastened thereto by a coating of adhesive 50 on the outer surface of the heel portion 23. In accordance with the present invention, the heel is also secured to the shoe by the clamping devices 37 and 38. In order to provide a soft, yieldable and sure gripping surface for the clamping devices, the heel portion 23 of the shoe is preferably cutaway at each side of the shoe as indicated at 51 and a strip of felt 52 inserted in said cutaway portion between the heel portion 23 and the upper 21 of the shoe.

When the heel is applied to the heel portion 23 and secured by adhesive, the clamping devices are in open inoperative position as shown in Fig. 4, with their flanges 41 slightly above the inner surface of the heel portion 23. The finger 47 of each latching device 46 is then swung inwardly around its pivot pin 45 thereby swinging the ears 48 around counterclockwise as viewed in Fig. 4, the edges of the ears camming against the outer extreme ends of the respective plates 30 and 31 swinging the body 40 of the clamp inwardly toward the body 25 of the heel 24 and bringing its flange 41 over the felt strip 52 as shown in Fig. 5. Continued inward swinging of the finger 47 forces the body portion 40 downwardly bringing its flange 41

into tight gripping and interlocking relation with the felt strip 52 and wedging the curved portion 44 of the strap 42 between the wall edges of the slot 35 of plate 30 as shown in Fig. 5, the finger 47 moving into locking position over the curved portion 44 of the strap with the pointed edges 49 of the ears 48 pressed against the respective plate such as plate 30 as shown in Fig. 3. This securely locks the clamp in position and securely fixes the heel on the shoe.

In the modified form of frame shown in Fig. 10, the connecting plates 32, 32 of the form of Figs. 1 to 9, inclusive, are omitted and the outer strap or plate 27' is formed with end extensions 60 for connecting the plates 30' and 31'. In all other respects, the form of frame shown in Fig. 10 is similar to the form shown in Figs. 1 to 9, inclusive, and similar reference numerals are used to indicate similar parts thereof.

In the modified form of clamping device shown in Figs. 11 and 12, the upwardly overlapping extension 44" of the strap portion 42" of the clamping body 40" is slightly bent instead of being curved as in the form of Figs. 1 to 9, inclusive. The finger member 47" of the latching device is also inwardly bent instead of being curved and is formed with a semi-spherical detent member 65 on the outer surface of its free end. A latch member 66 pivoted at one end on a pivot pin 67 extends through the overlapping extension 44" and is formed with a hook 68 at its other end having an opening 69 therein adapted to seat yieldingly on the detent member 65 when the latch member is swung to operative position as shown in Figs. 11 and 12. The latch member 66 is shown in unlatched position in dotted lines in Fig. 11.

In all other respects the clamping device of Figs. 11 and 12 is similar to the clamping device shown in Figs. 1 to 9, inclusive, and similar reference numerals are used to indicate similar parts.

The modified form of clamping device shown in Figs. 13 to 15, inclusive, differs from the form shown in Figs. 11 and 12 in that the latching member comprises a sleeve 70 slidably mounted on the overlapping extension 44" and has a hook 71 formed on the front of its upper edge adapted to interlock with the top end of the finger 47". A protuberance 72 on the top end of the overlapping extension 44" limits the upward movement of the sleeve 70. The latching sleeve 70 is shown in unlatching position in dotted lines in Fig. 14.

In all other respects the clamping device of Figs. 13 to 15, inclusive, is similar to the form of Figs. 11 and 12 and similar reference numerals are used to indicate similar parts.

While I have illustrated and described the preferred embodiments of my invention, it will be understood that changes in details might be made without departing from the principle of the invention.

Having thus described my invention what I claim as new and desire to secure by United States Letters Patent is:

1. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body, and devices on the projecting ends of the straight plates for clamping the heel onto a shoe.

2. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel

being rigidly connected thereto, said straight plates projecting outwardly from both sides of the body of the heel, and devices on the projecting ends of the straight plates for clamping the heel onto a shoe.

3. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel onto a shoe, said clamping devices each including a metal body pivotally mounted on a projecting end of one of said straight plates and an inwardly directed flange on the metal body adapted to engage a portion of a shoe and clamp the heel thereon.

4. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel onto a shoe, said clamping devices each including a metal body pivotally mounted on a projecting end of one of said straight plates, an inwardly directed flange on the metal body adapted to engage a portion of a shoe and clamp the heel thereon, and means for locking the flanged body in clamped condition.

5. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel onto a shoe, said clamping devices each including a triangular-shaped metal body having an inwardly directed flange along its wide end, an integral strap portion depending from the apex end of the body, said strap portion being pivotally mounted on a projecting end of one of said straight plates, and a locking latch pivotally supported on the strap portion and interlocking with said projecting end for locking the clamping body in clamped condition.

6. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel

onto a shoe, said clamping devices each including a metal body of triangular shape, an inwardly extending flange on the metal body at its wide end, an integral strap portion depending from the apex end of the metal body, said strap portion being turned upon itself forming an overlapping curved extension pivotally mounted on a projecting end of one of said straight plates, and a locking latch pivotally supported on said strap portion and interlocking with said projecting end for locking the clamping body in clamped condition.

7. A rubber heel for men's shoes comprising a body of rubber having a metal frame embedded therein including a pair of outer and inner horse-shoe shaped spaced plates connected midway their ends and having aligned slots in their ends, a straight plate disposed perpendicularly to the plane of the bodies of the curved plates spanning the space between the ends of said spaced plates and protruding through and outwardly of the slots therein, another straight plate disposed in the same plane as the first-named straight plate spaced outwardly thereof and being rigidly connected thereto, said straight plates projecting outwardly from both sides of the body of the heel, and devices on the projecting ends of the straight plates for clamping the heel onto a shoe, said clamping devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.

8. A rubber heel for men's shoes comprising a body of rubber having a metal frame embedded therein including an outer horse-shoe shaped plate, an inner horse-shoe shaped plate spaced from said outer plate, said outer plate having its ends extended beyond the ends of the inner plate, the ends of the plates being slotted, said outer plate having slots aligned with the slots in the ends of the inner plate, a straight plate disposed in a plane perpendicular to the plane of the bodies of the horse-shoe shaped plates and extending across the space between the ends of the inner plate and extending through the aligned slots in the outer and inner plates and outwardly of the outer plate, another straight plate disposed in the same plane as the first-named straight plate extending across the space between the ends of the outer plate and through and beyond the slots in the ends of said outer plate, the ends of said straight plates extending outwardly beyond both sides of the body of the heel, and devices on the ends of said straight plates for clamping the heel onto a shoe.

9. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.
10. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.
- 25
11. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.
- 30
12. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.
- 35
13. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a latch member pivotally mounted on the upwardly extending portion of the strap portion adapted to be swung over the end of the finger portion for locking the clamping device in clamped condition.
- 40
14. A rubber heel for men's shoes comprising a body of rubber having a metal frame embedded therein including a pair of inner and outer spaced curved plates and a pair of straight plates disposed perpendicularly to the plane of the bodies of said curved plates, the ends of said straight plates projecting outwardly on both sides of the body of the heel and being provided with slots, and devices on the projecting ends of the straight plates for clamping the heel onto a shoe, said devices each including a metal body of triangular shape, an inwardly extending flange on the metal body at its wide end, an integral strap portion depending from the apex end of the metal body and extending through the slot in the end of the respective straight plate, said strap portion being turned upon itself forming an upwardly extending bent portion overlapping the strap portion, a locking latch pivotally supported on said strap portion adjacent its bottom end including a finger portion adapted to be swung into overlapping relation with said upwardly extending portion of the strap portion, and a split sleeve slidably mounted on said upwardly extending portion having a hook on its upper outer edge for interlocking with the upper end of the finger portion of the latch for locking the clamping device in clamped condition.
